UNITED STATES PATENT OFFICE.

HERMAN C. PRIEBE, OF BLUE ISLAND, ILLINOIS.

FRICITION DRAFT GEAR.

Application filed January 29, 1921. Serial No. 440,986.

To all whom it may concern:

Be it known that I, HERMAN C. PRIEBE, a citizen of the United States, residing at Blue Island, in the county of Cook and 5 State of Illinois, have invented a certain new and useful Improvement in Friction Draft Gears, of which the following is a full, clear, concise, and exact description.

My invention relates to friction draft 10 gears that employ coupler operated followers, friction producing blocks, and spring mechanism for reversing the coupler effected movements of the followers and blocks. In practicing my invention I employ a 15 single follower movable by the coupler in either direction in the line of draft, at least one block frictionally engaging the follower and moved thereby transversely of the line of draft, this block also engaging, prefer- 20 ably frictionally, a complementary part of the gear. There is also an added block frictionally engaged by the first and moved in the line of draft by the first block, and a spring opposing the movement of the 25 added block by the first and serving, when free to act, to reverse the coupler effected movements of said blocks and follower.

In the preferred embodiment of the invention there are two blocks frictionally engaged by the follower and moved thereby toward each other transversely of the line of draft by the follower and away from each other by the spring, when free to act, through the spreading action effected on the 30 two blocks by the added block, the first two blocks not only both frictionally engaging the follower but also the added block and the friction surface provided upon the coupler. The follower is desirably made 35 hollow to constitute it a spring barrel to house the springs.

I will explain my invention more fully by reference to the accompanying drawings showing the preferred embodiment thereof and in which Fig. 1 is a view in plan with parts broken away and parts shown in section of enough of a friction draft gear to enable my invention to be understood; Fig. 2 is a sectional view on line 2—2 of Fig. 1; Fig. 3 is a view of parts as they appear in Fig. 2 but with the coupler under pushing strains; Fig. 4 is a sectional view on line 4—4 of Fig. 3; and Fig. 5 is a perspective view of some of the component parts of the 40 gear of my invention in separated relation.

Like parts are indicated by similar characters of reference throughout the different figures.

I have illustrated parts of two center or draft sills 1 and 2 that form structural parts 60 of the underframe of a car. These center sills carry cheek plates 3 and 4 upon their inner faces. A carrier iron 5 is bolted to the bottom flanges of the center sills and underlies the space between the center sills 65 for the purpose of supporting the coupler yoke 6 that is suitably connected with the coupler stem 7 as by means of a key 8. The coupler structure is further supported by causing the key to pass through and slide 70 within slots 9 formed in the center sills and the forward cheek plates 3. The coupler yoke 6 embraces a follower 10 that is supported by the coupler yoke. This follower is limited in its outward movement by the 75 outer cheek plates 3 and in its inward movement by the cheek plates 4. It is desirably made hollow or pocketed to form a spring barrel that houses a spring 11. The upright opposing sides of the hollow portion of the 80 follower is formed with V-shaped openings or spaces 12 that taper outwardly. Two friction blocks 13 are sloped outwardly to afford surfaces that are in frictional engagement with the sloping surfaces of the 85 openings 12 in the follower. A friction block 14, triangular in cross section, is interposed between and frictionally engaged by the friction blocks 13 and is pressed upon by the spring 11 toward the inner end 15 of 90 the coupler yoke 6. This yoke end 15 has a friction surface 16 that is enclosed by the yoke and is angular to the line of draft, this friction surface being frictionally engaged by the blocks 13 in the movement of these 95 blocks toward and from each other transversely of the line of draft. When the coupler is subject to sufficient pushing strains the coupler butt engages the outer end of the follower 10 and moves this follower inwardly, the follower then frictionally engaging and forcing the friction blocks 13 to move toward each other transversely of the line of draft. When the friction blocks are thus moved toward each other they 100 frictionally engage and move the friction block 14 toward the outer end of the coupler and against the force of the spring 11 that is interposed between this block and the outer end of the follower. In the movement of 105 110

the blocks 13 toward each other these blocks rub upon the friction surface 16 of the coupler yoke and cause additional friction that serves, in conjunction with the friction 5 elsewhere produced, to retard the effect of the coupler blows. When the coupler is subject to sufficient pulling strain the inner end of the yoke 6 presses outwardly upon the blocks 13 that in turn press upon the 10 sloping surfaces of the openings 12 and the sloping surfaces of the triangular block 14 whereby the blocks 13 are then also moved inwardly transversely of the line of draft and block 14 is again moved outwardly. 15 Whenever the draft strains upon the coupler are sufficiently reduced the spring 11 is effective to reverse the movements of the friction elements that were occasioned by the action of the coupler. I have thus devised 20 a construction employing a single follower that is effective in moving the blocks 13 toward each other transversely of the line of draft whether the coupler be pulled upon or pushed upon with sufficient force. 25 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a friction draft gear, the combination 30 with a coupler yoke having a friction surface angular to the line of draft; of a single follower movable in the line of draft; a block structure frictionally engaging the aforesaid friction surface and the follower and moved by the follower transversely of the line of draft; a second block structure frictionally engaging the first and moved in the line of draft by the first block structure; a spring opposing the movement of 40 the second block structure by the first and serving, when free to act, to reverse the gear effected movements of said block structures and follower; and draft sills having motion limiting formations with which the block structure that frictionally engages the aforesaid surface upon the coupler yoke is engageable.

2. In a friction draft gear, the combination 45 with a coupler yoke having a friction surface angular to the line of draft; of a single follower movable in the line of draft; two blocks frictionally engaging the aforesaid friction surface and the follower and moved by the follower transversely of the line of draft and toward each other; an additional block frictionally engaged by and between the aforesaid blocks and moved thereby in the line of draft by the first aforesaid blocks when the first aforesaid blocks are brought closer together; a spring opposing the movement of said additional block by the first aforesaid blocks and serving, when free to act, to reverse the gear effected movements of said blocks and follower, the first aforesaid blocks each having two places of engagement with the follower adjacent the ends of such block and an intermediate place of engagement with the additional block; and draft sills having motion limiting formations with which the block structures that frictionally engage the aforesaid surface upon the coupler yoke is engageable.

3. In a friction draft gear, the combination 50 with a coupler yoke having a friction surface angular to the line of draft; of a single follower movable in the line of draft; a block structure frictionally engaging the aforesaid friction surface and the follower and moved by the follower transversely of the line of draft; a second block structure frictionally engaging the first and moved in the line of draft by the first block structure; a spring opposing the movement of the second block structure by the first and serving, when free to act, to reverse the gear 55 effected movements of said block structures and follower, the first aforesaid block structure having two places of engagement with the follower adjacent the ends of this block structure and an intermediate place of engagement with the second block structure; and draft sills having motion limiting formations with which the block structure that frictionally engages the aforesaid surface upon the coupler yoke is engageable.

4. In a friction draft gear, the combination 60 with a coupler yoke having a friction surface angular to the line of draft; of a single follower movable in the line of draft; two blocks frictionally engaging the aforesaid friction surface and the follower and moved by the follower transversely of the line of draft and toward each other; an additional block frictionally engaged by and between the aforesaid blocks and moved thereby in the line of draft by the first aforesaid blocks when the first aforesaid blocks are brought closer together; a spring opposing the movement of said additional block by the first aforesaid blocks and serving, when free to act, to reverse the gear effected movements of said blocks and follower, the first aforesaid blocks each having two places of engagement with the follower adjacent the ends of such block and an intermediate place of engagement with the additional block; and draft sills having motion limiting formations with which the block structures that frictionally engage the aforesaid surface upon the coupler yoke is engageable.

5. In a friction draft gear, the combination 65 with a coupler yoke having a friction surface angular to the line of draft; of a single follower movable in the line of draft; a block structure frictionally engaging the aforesaid friction surface of the follower and moved by the follower transversely of the line of draft; a second block structure

- frictionally engaging the first and moved in the line of draft by the first block structure; a spring opposing the movement of the second block structure by the first and serving, when free to act, to reverse the gear effected movements of said block structures and follower, the first aforesaid block structure having two places of engagement with the follower adjacent the ends of this block structure and an intermediate place of engagement with the second block structure, said follower being hollow to constitute it a spring barrel in which said spring is disposed; and draft sills having motion limiting formations with which the block structure that frictionally engages the aforesaid surface upon the coupler yoke is engageable.
6. In a friction draft gear, the combination with a coupler yoke having a friction surface angular to the line of draft; of a single follower movable in the line of draft; two blocks frictionally engaging the aforesaid friction surface and the follower and moved by the follower transversely of the line of draft and toward each other; an additional block frictionally engaged by and between the aforesaid blocks and moved thereby in the line of draft by the first aforesaid blocks when the first aforesaid blocks are brought closer together; a spring opposing the movement of said additional block by the first aforesaid blocks and serving, when free to act, to reverse the gear effected movements of said blocks and follower, the first aforesaid blocks each having two places of engagement with the follower adjacent the ends of such block and an intermediate place of engagement with the additional block, said follower being hollow to constitute it a spring barrel in which said spring is disposed; and draft sills having motion limiting formations with which the block structures that frictionally engage the aforesaid surface upon the coupler yoke is engageable.
7. In a friction draft gear, the combination with a coupler yoke having a surface angular to the line of draft; of a single follower movable in the line of draft; a block structure engaging the aforesaid surface and the follower and moved by the follower transversely of the line of draft; a second block structure frictionally engaging the first and moved in the line of draft by the first block structure; a spring opposing the movement of the second block structure by the first and serving, when free to act, to reverse the gear effected movements of said block structures and follower; and draft sills having motion limiting formations with which the block structure that frictionally engages the aforesaid surface upon the coupler yoke is engageable.
8. In a friction draft gear, the combination with a coupler yoke having a surface angular to the line of draft; of a single follower movable in the line of draft; two blocks engaging the aforesaid surface and the follower and moved by the follower transversely of the line of draft and toward each other; an additional block frictionally engaged by and between the aforesaid blocks and moved thereby in the line of draft by the first aforesaid blocks when the first aforesaid blocks are brought closer together; a spring opposing the movement of said additional block by the first aforesaid blocks and serving, when free to act, to reverse the gear effected movements of said blocks and follower, the first aforesaid blocks each having two places of engagement with the follower adjacent the ends of such block and an intermediate place of engagement with the additional block; and draft sills having motion limiting formations with which the

block structures that frictionally engage the aforesaid surface upon the coupler yoke is engageable.

11. In a friction draft gear, the combination with a coupler yoke having a surface angular to the line of draft; of a single follower movable in the line of draft; a block structure engaging the aforesaid surface of the follower and moved by the follower transversely of the line of draft; a second block structure frictionally engaging the first and moved in the line of draft by the first block structure; a spring opposing the movement of the second block structure by the first and serving, when free to act, to reverse the gear effected movements of said block structures and follower, the first aforesaid block structure having two places of engagement with the follower adjacent the ends of this block structure and an intermediate place of engagement with the second block structure said follower being hollow to constitute it a spring barrel in which said spring is disposed; and draft sills having motion limiting formations with which the block structures that frictionally engage the aforesaid surface upon the coupler yoke is engageable.

12. In a friction draft gear, the combination with a coupler yoke having a surface angular to the line of draft; of a single follower movable in the line of draft; two blocks engaging the aforesaid surface and the follower and moved by the follower transversely of the line of draft and toward each other; an additional block frictionally engaged by and between the aforesaid blocks and moved thereby in the line of draft by the first aforesaid blocks when the first aforesaid blocks are brought closer together; a spring opposing the movement of said ad-

ditional block by the first aforesaid blocks and serving, when free to act, to reverse the gear effected movements of said blocks and follower, the first aforesaid blocks each having two places of engagement with the follower adjacent the ends of such block and an intermediate place of engagement with the additional block, said follower being hollow to constitute it a spring barrel in which said spring is disposed; and draft sills having motion limiting formations with which the block structures that frictionally engage the aforesaid surface upon the coupler yoke is engageable.

13. In a friction draft gear the combination with a coupler yoke having a surface angular to the line of draft; of motion resisting friction producing mechanism including a friction block structure engageable with the aforesaid surface upon the coupler yoke that is angular to the line of draft; and draft sills having motion limiting formations with which the block structure that frictionally engages the aforesaid surface upon the coupler yoke is engageable.

14. In a friction draft gear, the combination with a coupler yoke; of friction producing mechanism operated by the coupler yoke and including a horizontal friction block structure; and draft sills between which said friction producing mechanism is disposed, the aforesaid horizontal friction block structure extending substantially across the space between the draft sills, said draft sills having motion limiting formations with which said horizontal friction block structure is engageable.

In witness whereof, I hereunto subscribe my name this twenty-fourth day of December A. D., 1920.

HERMAN C. PRIEBE.
